UNITED STATES PATENT OFFICE.

MARTIN MURPHEY, OF BROOKLYN, ASSIGNOR TO WILLIAM McDONOUGH,
OF NEW YORK, N. Y.

WINDOW-CORNICE.

SPECIFICATION forming part of Letters Patent No. 224,466, dated February 10, 1880.

Application filed October 15, 1879.

To all whom it may concern:

Be it known that I, MARTIN MURPHEY, of Brooklyn, in the county of Kings and State of New York, have invented certain new and useful Improvements in Window-Cornices; and I do hereby declare that the following is a full, clear, and exact description of the invention, which will enable others skilled in the art to which it appertains to make and use the same, reference being had to the accompanying drawings, which form a part of this specification.

Figure 1 is a front view. Fig. 2 is a top view. Fig. 3 is a rear view. Fig. 4 is a cross-section.

Corresponding parts in the several figures are denoted by like letters of reference.

This invention relates to certain cornices of that class which are adjustable or capable of being extended so as to fit windows of different widths; and it consists in certain improvements in the construction of the same, which will be hereinafter fully described, and particularly pointed out in the claims.

My improved cornice consists of two pieces of moldings, A A, each of which may be provided at one end with a return-piece, B.

The moldings A are so formed as to serve two purposes—to wit, first, ornamentation; and, second, to present two reverse grooves, C C, adapted to receive corresponding tongues D D upon the rear side of a third piece of molding, E, which, as will be seen, is so constructed as to fit upon the face of the moldings A.

The face of the molding E may be like that of the moldings A, or it may be provided with any suitable ornamentation.

The central molding, E, serves to connect the side moldings, A A, which may be slid together or apart to any desired extent, thus fitting the cornice to windows of various widths.

Suitable ornaments F F, also provided upon

their rear sides with tongues to engage the grooves C, may be slid upon the moldings A, 45 and adjusted at the ends, or in any desired position.

In the cross-section, Fig. 4, I have shown how the grooves C C are provided upon their inner faces with thin narrow strips H H, the 50 object of which is to raise the sliding pieces from the face of the stationary piece, causing an intervening space. (Denoted by the letter I, Fig. 4.) The polished face of the lower molding is thereby protected from injury by friction when the cornice is extended or folded. 55

My improved adjustable cornice is simple in construction, it presents a handsome appearance, and is capable of being extended to nearly the full combined length of its component parts. 60

I am aware that adjustable cornices are not new, broadly. Such, therefore, I do not claim; but,

Having thus described my invention, I 65 claim and desire to secure by Letters Patent of the United States—

1. The combination, with moldings A A, having their ornamental faces so formed and beaded as to present retaining-grooves C C, 70 of the center molding, E, having tongues on its rear side to engage therewith and form an adjustable cornice, as and for the purpose set forth.

2. As an improvement in adjustable cornices, 75 the moldings A A, having grooves C C, provided upon their inner faces with strips H H, in combination with a central connecting-piece, E, having tongues D D, as set forth.

In testimony that I claim the foregoing as 80 my own I have hereto affixed my signature in presence of two witnesses.

MARTIN MURPHEY.
